UNITED STATES PATENT OFFICE.

HENRY C. EGERTON, OF RIDGEWOOD, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

REISSUED

1,400,039.

Specification of Letters Patent. Patented Dec. 13, 1921.

Application filed December 27, 1918. Serial No. 268,482.

To all whom it may concern:

Be it known that I, HENRY C. EGERTON, a citizen of the United States, residing at Ridgewood, in the county of Bergen, State 5 of New Jersey, have invented certain new and useful Improvements in Signaling Systems, of which the following is a full, clear, concise, and exact description.

This invention relates to electric signal- 10 ing systems, and more particularly to the production and utilization of impulses for synchronizing purposes.

The principal object of this invention is to combine a plurality of high frequency 15 currents in such a manner that the resultant frequency or beat oscillations may be employed to keep a plurality of movable members in unison or synchronism, this condition to be insured regardless of whether 20 signaling impulses are being transmitted or not.

The invention contemplates the employment of two alternating current sources giving different frequencies connected in series 25 or parallel and arranged to feed into a repeater or line circuit. If two alternating current sources having slightly different frequencies are impressed upon a line circuit, beat oscillations are produced the most im- 30 portant of which have a frequency equal to the difference in the frequencies of the two sources. If the two different frequencies are sent into a vacuum tube repeater, not only the original frequencies come out, but 35 also a low electrical oscillation, the frequency of which depends upon the number of beats occurring due to combining the two currents of higher frequencies. It is this low frequency current which it is proposed 40 to use for maintaining synchronism. These beats may be manifested as a sound or noise in a receiving instrument or as illustrated in the present application, they may be employed for performing work such as the 45 operation of an electromagnet. The production of beat oscillations in the present instance is accomplished by generating two frequencies, for example, oscillations of 400 and 404 cycles and these frequencies may in 50 a telegraph system be superimposed on the signaling currents without interfering with the effective transmission of the latter.

The above and other objects of this invention will be set forth in the following de-

scription and claims and will be more 55 readily understood by reference to the accompanying drawing wherein the invention is disclosed as applied to a printing telegraph system of the rotary distributor type.

In the accompanying drawing A represents a sending station and B a receiving station. At station A there is provided one or more impulse transmitters 10, each comprising a group of selectively operable transmitter contacts 11, 12, 13, 14 and 15. The 60 contacts are connected to a source of A. C. signaling current 45 and are adapted when actuated to connect source of current 45 to corresponding segments 16, 17, 18, 19 and 20 respectively of distributor 21. 70

The transmitter 10 may be of the keyboard type or it may consist of an automatic transmitter operated by a perforated tape or the like. If an automatic transmitter is employed the segments 70 and 71 may 75 be used to connect battery 72 over the distributor brush 23 to a suitable magnet (not shown) for advancing the perforated type.

A distributor arm 22 carries a brush 23 which is adapted to sweep over the segments 80 of the distributor face and connect the segments of each group sequentially with a common ring 24 which, as illustrated, comprises a plurality of segments strapped together. The distributor brush arm 22 is 85 preferably normally under tension tending to rotate and its rate of travel may be governed by electromagnet 25 through the instrumentality of the escapement mechanism 26 and ratchet 27 or the distributor brush 90 arm 22 may be positively driven by a ratchet and pawl mechanism similar to the escapement mechanism illustrated.

At station B there is provided a rotary distributor 28, escapement mechanism 29, 95 etc., which is similar to the mechanism described at station A. Connected to segments 31, 32, 33, 34 and 35 of distributor 28 are receiving magnets 36, 37, 38, 39 and 40 respectively. Whenever any of the transmitter contacts 11 to 15 are closed and the distributors are set in operation corresponding receiving magnets 36 to 40 will be operated by current from source 45. For example, if transmitter contacts 11 and 14 are closed, 100 circuits will be completed sequentially from ground 42, impedance 43 and 44, distributor ring 24, brush 23, segment 16, contact 11, 105

to source of current 45, and from brush 23, segment 19, contact 14 to source of current 45, thence by conductor 46, line L, conductor 41, to receiving magnets 36 and 39, segments 5 31 and 34 respectively, brush 47, distributor ring 48, impedance 49 and 50 to ground at 51. Circuits through other receiving magnets would be established in a like manner by the closure of additional transmitter contacts. The receiving magnets may be employed to operate selecting mechanism of a receiving printing telegraph or they may be employed in connection with any suitable receiving or recording device. The generator 45 may be assumed, for example, to produce a low frequency signaling current of 60 or 75 cycles. If desired, a source of direct current battery may be substituted for signaling current in place of the alternating current source 45.

Two sources of alternating currents from which the synchronizing oscillations are derived are represented at 52 and 53. The generator 52 may be assumed, for example, 25 to generate a frequency of 400 cycles and the generator 53 may be assumed to generate a frequency of 404 cycles, although other frequencies may obviously be employed. These sources are arranged to impress currents on the line L which also carries the signaling currents and it is therefore necessary to provide suitable filters and amplifiers to prevent interference between the synchronizing currents and the signaling currents and to enable the beat oscillations to effect the operation of the synchronizing mechanism.

The filter 55 comprising one or more condensers 56 and inductive resistance 57 may 40 be arranged to admit, for example, a minimum of 150 cycles thereby admitting the assumed higher frequencies and not the signaling frequency. Associated with the filter 55 is a repeater or combiner 58 which is a 45 three element vacuum tube of the audion type and which takes up the two original frequencies and gives out in addition to the original frequencies the summation of the two frequencies and the difference in the 50 two frequencies or the beat frequency. The filament 4 of the repeater is heated by battery 5, the grid 3 is supplied with negative potential by means of battery 6 and the space current in the output circuit 2 is supplied by battery 7. Connected to the output circuit 2 of the repeater 58 is a filter 60 comprising a condenser 59 and inductive resistance 61 which is arranged to admit the beat frequency only, or in the present case 55 say a maximum of 5 cycles. These filtered beat oscillations are then sent into a vacuum tube amplifier 62 and amplified sufficiently to effect the operation of the distributor magnet 25. The magnet 25 is 60 shown in the present instance as controlling

the escapement mechanism of a continuously driven distributor, which may be frictionally connected to the shaft of a motor.

At station B are provided filters 64 and 65, a repeater 66 and an amplifier 67 which correspond to filters 55 and 60, repeater 58 and amplifier 62, respectively at station A. Across the output circuits of filters 60 and 65 are connected resistances 80 and 81, respectively. These resistances are employed to 70 permit the proper operation of repeaters 58 and 66. The filters, repeater and amplifier at station B are arranged to permit the beat oscillations to effect the operation of distributor magnet 68 and cause it to step a 75 distributor 28 in synchronism with the distributor 21. The means provided at station B for filtering, repeating and amplifying the synchronizing currents is a duplication of 80 that already described in connection with station A and therefore a detailed description of the apparatus at station B is believed to be unnecessary.

While the magnets 25 and 68 are shown as 85 controlling the escapement mechanism of continuously driven distributor arms, the magnets may be employed to operate La Cour motors as are well known in the art or they may be employed to control the correcting mechanism of a synchronizing system such as disclosed in a copending application, Serial No. 129,462 filed November 4, 1916 for Paul M. Rainey.

At station A is a filter 73 comprising a condenser 74 and inductive resistance 43 and 90 44, and at station B is a corresponding filter 75 comprising a condenser 76 and inductive resistance 49 and 50. Each of these filters is arranged to admit only the signaling current oscillations or, for example, a maximum of 95 100 105 150 cycles.

Associated with each quadrant of the receiving distributor is a pair of local segments 77 and 78 which may be utilized to conduct current from battery 79 over the distributor brush 47, to a printing magnet (not shown) to record the characters as determined or set up by the selective operation of the magnets 36 to 40, inclusive.

This invention is not limited to the employment of the particular synchronizing frequencies designated or to the particular type of synchronizing apparatus illustrated but is intended to cover broadly the employment of beat oscillations or the oscillations 110 produced by the combination of a plurality of unequal current frequencies for maintaining synchronism between a plurality of movable members.

What is claimed is:

1. The method of maintaining synchronism between two rotatable members operatively interconnected by a transmission line and adapted to be operated by independent sources of motion which consists in send- 115 120 125 130

ing over said line currents of different frequencies, and employing the beat oscillations produced by combining said frequencies to control the operation of said rotatable members.

2. Electrical synchronizing apparatus comprising means for impressing on a line circuit currents of predetermined character, means for combining the currents to produce beat oscillations, and means controlled by the beat oscillations for maintaining synchronism.

3. In a synchronizing system the combination of a transmission line, means for applying currents of different frequencies to said line, a plurality of members to be synchronized, and means responsive to the beat oscillations produced by said different frequencies for controlling the operation of said members.

4. In a synchronizing system the combination of a transmission line, means for applying currents of different frequencies to said line, a plurality of rotatable members, devices for controlling the rotation of said members, and means responsive to the beat oscillations produced by said currents for operating said devices.

5. Electrical synchronizing apparatus comprising a sending station and a receiving station, a transmission line interconnecting said stations, distributor mechanism at each of said stations, means for impressing upon the line a plurality of currents of different frequencies, means for altering the frequency of said currents, and means re-

sponsive to the altered frequency for controlling the said distributors.

6. Electrical synchronizing apparatus comprising a sending station and a receiving station, means at the sending station for transmitting groups of signaling impulses, means at the receiving station responsive to the impulses transmitted from the sending station, independently driven distributors at each of said stations, means for transmitting a plurality of synchronizing currents of different frequencies, means at each of said stations for separating the signaling currents from the synchronizing currents, means at each of said stations for altering the synchronizing currents, and means at each of said stations responsive to the altered currents for operating said distributors in synchronism.

7. Electrical synchronizing apparatus comprising a transmitting station and a receiving station interconnected by a transmission line, movable members at each of said stations, means at the transmitting station for transmitting signaling impulses, means for superimposing on the signaling impulses currents of high frequency, means at the receiving station responsive to the signaling impulses, and means at each of said stations responsive to the high frequency currents for maintaining said members in synchronism.

In witness whereof, I hereunto subscribe my name this twenty-fourth day of December, A. D. 1918.

HENRY C. EGERTON.
